CARBURETOR

Jean Marie Piat, Villeurbanne, France

Application May 24, 1933, Serial No. 672,714
In France May 31, 1932

8 Claims. (Cl. 261—41)

My invention relates to carburetors for automobile engines and the like and it has for its object to provide a carburetor wherein the fuel is perfectly atomized for any adjustment of the 5 throttle valve. Another object of my invention is to dispense with the so-called low-running jets which are generally necessary in the known carburetors. Furthermore my invention has also for its object to permit of adjusting at will the 10 section of the jet which regulates the fuel feed.

The carburetor according to my invention is provided with a plurality of nozzles which communicate with a mixing chamber, one of said nozzles being axial, and the throttle means are 15 in the form of a sliding piston bell provided with bores registering with said nozzles in such a manner that at slow running the axial nozzles work as a fuel nozzle proper, the other nozzles admitting air into the mixing chamber, and that at 20 high speeds all the nozzles work as fuel nozzles feeding an emulsion of air and fuel from the mixing chamber into the suction pipe.

In the annexed drawings:

Fig. 1 is a vertical and longitudinal section of 25 the whole of the carburetor, the movable parts of which are shown in the position of rest corresponding to the stoppage of the motor.

Fig. 2 is a vertical transversal section on line 30 II—II of Fig. 1, and drawn to a larger scale.

Fig. 3 is a view from the underside of the piston bell.

Fig. 4 is a view in vertical section of the piston-bell at the position of partial rising.

Fig. 5 is an end view of the carburetor showing 35 the air inlet.

The carburetor comprises a cylindrical constant level tank 1 for the fuel which is fed through the cover 5 of known construction and comprising a needle valve and float etc. (Fig. 1). The bottom 40 1^a is inclined in order to permit the complete emptying by the orifice closed by a screw stopper 3 and also to permit of easily cleaning the carburetor, as it will be explained. The tank 1 is in a single casting with a lateral appendix or 45 nose 2 of which the lower face is inclined and prolongs the bottom 1^a while the upper face 2^a is flat and parallel with the level N. N. As shown in Fig. 1 the nose 2 is provided through all its length with a cylindrical hole parallel to its lower 50 inclined face in order to cause communication of the base of the tank with the extremity of the nose 2. In this hole there is inserted a tube 6 the lower screw threaded end of which projects into the interior of the tank and receives a nut 55 7, while the upper extremity passing the nose 2

comprises a part of larger diameter 6^a forming an annular cavity opening upwardly. Part 6^a is provided with an ear 6^b serving as a support to the axis of articulation 24 of a regulatable abutment 25 for one of the ends of a flexible transmission such as 26 having its cable 27 wound on a barrel 28 covering the upper extremity of tube 6 and inserted in the annular cavity of the cylindrical part 6^a.

Tube 6 is bored downwardly along a certain 65 length to receive a plug 8 the wall of which comprises at a point of its length a crown having five orifices a—b—c—d—e constituting sunk jets possessing different and progressive sections starting from the orifice a as shown in the section illustrated in Fig. 2. The situation of this crown of jets is in concordance with a single hole 9 formed in the wall of tube 6 and oriented to coincide with the lower orifice of a vertical conduit 10 formed in the interior of the nose 2 so as 70 to cause the interior of the plug 8 to communicate by means of one of the jets with a mixing chamber 11 arranged in the thickness of the nose 2. This chamber 11 is horizontal and parallel with level N. N. above which it is situated. 75 The upper wall of the said chamber is traversed by three holes arranged in line and bored to receive three nozzles 12, 13, 14 allowing the chamber to communicate with the exterior. Nozzles 13, 14 are identical and are each formed 80 by a simple tube open at both ends of which the lower one communicates with chamber 11 while the upper one the orifice of which is widened out 85 leads into a blind bore of a piston bell 16 serving as a throttle valve. The middle nozzle 12 is 90 also a tube but is closed at both ends the wall of this tube being provided with lateral holes 12^b and 12^c communicating together by the axial conduit 12^a. The holes 12^b lead into the interior 95 of the chamber 11 while the holes 12^c lead into the interior of a bore of two successive and different diameters 15^a and 15^b formed in the lower part of a rod 15 axially traversing the vertical bell 16. This bell is slidable in a cylinder 5 cast in a single piece with the cover 5 100 of tank 1 and maintained in position by a pin 39 integral with the nose 2 (Fig. 1). The fastening of the cover on the tank and of the cylinder on the face 2^a of nose 2 is obtained by the pressure of a nut 40 screwed onto the screw-threaded 105 end of pin 39. The lower part of the axial rod 15 comprises two holes 17 and 17^a of different sections and formed in diametrically opposite points in the wall corresponding to the upper bore 110 of smaller diameter 15^a and a notch 18 formed

on the lower edge of rod 15. The lower extremity of the bell 16 comprises a transverse channel 19 starting from the housing orifice of the lower part of rod 15 and extending just to the outer edge of bell 16.

Fig. 3 clearly shows this notch 18 and channel 19 as well as the entrance of the three bores 15^a 16^b 16^c which cap the three nozzles 12, 13 and 14. In Figs. 2 and 4 there is illustrated an inclined conduit 20 pierced at the base of bell 16 in order to cause bore 15^a to communicate with the widened outlet of conduit 19 when rod 15 is turned in such a way that hole 17^a is in concordance with the commencement of said conduit 20, and so that the hole 17 diametrically opposite coincides with a hole 16^a formed transversely for this purpose in the bell 16.

As shown in Fig. 3, notch 18 extends angularly for a considerable angle. Hole 17^a is also elongated as shown in Figs. 2 and 3. It follows that, when rod 15 is turned within bell 16, notch 18 and hole 17^a register with groove 19 and conduit 20 respectively during a part of the rotation, whilst on the contrary hole 17, which is circular, registers with hole 16^a only at a position. This permits of adjusting the degree of suction acting on nozzle 12, as it will be explained.

The actuation of bell 16 is effected in the known manner by a square 35, 36 articulated on an axis 37 integral with cylinder 5^a. Arm 36 is connected by a cable or rod to an actuating lever arranged on the dash-board of the vehicle. Arm 35 embraces a pin 38 fixed to the bell 16 and movable in a slide formed in the wall of cylinder 5^a.

The plug 8 which comprises the sunk nozzles a, b, c, d, e is of a suitable length so that its upper end 8^a sufficiently passes the upper extremity of the fixed tube 6 in order to be kept by the summit of the annular member 28 so that it may be fixed by a pin 8^b screwed into upper end 8^a. The extremities of this pin overlap and are housed in two recesses 28^a of member 28 on the bottom of which these extremities of the pin are applied owing to the presence of a spring plate 29 articulated on a boss of member 28 in order that the free end provided with a button 29^a can be brought above the end 8^a of plug 8 and exercises a strong pressure on this latter in order to maintain the crown of nozzles in concordance with hole 9. This method of mounting the plug 8 8^a allows its rapid removal for the inspection of the sunk nozzles and its equally rapid replacement. It will be easily grasped from Fig. 1 that the removal of plug 8 8^a and of screw stopper 3 permits of easily and completely cleaning the carburetor, which is a matter of importance.

In Fig. 2, 21 designates a tube adapted to be connected with the suction pipe of the motor and situated in a plane perpendicular to that of the longitudinal axis on which the section shown in Fig. 1 is made. The entrance of this tube 21 is placed in correspondence with the wide end outlet of the channel 19 of the bell 16 and with the outlet of the inclined conduit 20. It is diametrically opposite to an opening 33 which is formed in the wall of the fixed cylinder 5^a and constitutes the air inlet the section of which is adjusted by means of a sliding valve 34 (Fig. 2). This valve may be pivoted at 34^a, as shown in Fig. 5, or guided in any suitable manner.

The mixing chamber 11 (Fig. 2) is in communication with the atmosphere by the conduit 31 of a tube closed at the end and provided later-

ally with a calibrated orifice 31^a the section of which is entirely or partially uncovered by a ring 32 provided with an orifice 32^a. The angular displacement of this ring consequently permits a precise regulation of the admission of air to the chamber 11.

The operation is as follows:—

In Fig. 1 the bell 16 rests on the upper face 2' of the nose 2 and prevents any communication of the motor with the exterior. This is the position of complete repose corresponding with the stoppage of the motor. To effect starting the driver operates the governing handle of the square 35, 36 governing the bell 16; this first operation causes a slight ascent of the bell in order that its lower face arrives at the level of the lower part of the internal diameter of the tube 21, that is to say, at the position shown in Fig. 2 where the suction of the motor takes place through the channel 19 and notch 18 and through the conduit 20 and orifice 17^a, pass into the bores 15^a 16^b and in the interval separating the bottom of the bell 16 from the face 2' of the nose 2. It follows that this suction acts simultaneously on the air admission 33 and on the orifices 12^a through which it enters to follow the channel 12^a traversing the orifices 12^b and passing into the mixing chamber 11 then acting on the air inlet 31^a on conduit 10 and hole 9 to effect a suction of the fuel through the sunk jet which has been put in concordance by the conductor having effected the necessary displacements of the plug 8 by the transmission governing means 26.

It can be understood that the sucked fuel is atomized in the chamber 11 and forms with the air sucked in at the same time through the orifice 31^a an initial emulsion mixture which is fed through the orifices 12^b into the bores 15^a 15^b wherein is produced an energetic stirring and a new mixture of emulsion with secondary air 115 passing through the opening 33 below the valve 34 and passing into the first bore 15^b annularly to the ajutage 12. This gaseous mixture is sucked on the one hand through the conduit 19 and on the other hand through the conduit 20 and orifice 17^a and passing to the motor. This final mixture is very rich in fuel since the quantity of air is in a small proportion. The position shown in Fig. 2 corresponds then to the starting of the motor and also to slow running.

It will be observed that the degree of suction acting on nozzle 12 is easily adjustable by rotating rod 15 as above explained, since this rotation more or less closes the outlet of conduit 16^a which connects bore 15^a with the exterior.

It will also be understood that, owing to the circular shape in section of pipe 21 as opposed to the flat base of bell 16, the space situated beneath the base of bell 16 is not under suction. Thus the lateral bores 16^b and 16^c (Fig. 1) of bell 16 are practically under atmospheric pressure. Since the mixing chamber 11 is under suction, a current of air circulates downwardly from bores 16^b and 16^c into the mixing chamber. This obviates the known disadvantage of having too rich a mixture at low openings of the throttle means.

When the driver desires to increase speed he again actuates the lever 35, 36 in a gradual manner in order to cause a progressive rising of the bell 16 which uncovers little by little the three nozzles 12, 13, 14 but the suction can only act on the middle one 14 and consequently in the mixing chamber 11 and on the sunk jet which is in concordance with the conduit 10 as long as the nozzles 13, 14 are not sufficiently uncovered to allow 150

- passage to the suction; it results that the orifices 12^c will feed alone during a portion of the rising movement of the bell 16 and that the gaseous mixture will retain a certain richness in fuel 5 until the proportion of air increases from the fact of the increase of the sizes of the air inlet which is functional with the degree of elevation of bell 16. When bell 16 is sufficiently high, the space beneath its base is also under depression. 10 It follows that the outlets of nozzles 13 and 14 within bores 16^b and 16^c are also submitted to suction. This causes an upwardly current of fluid through said nozzles. There is thus produced a second suction of emulsion of air and 15 fuel in the chamber 11 at the same time that the volume of secondary air will increase. Consequently for a given calibration of the embedded jet (for example the smallest jet *a*) one will obtain a very varied range of proportions of fuel 20 and air by the sole fact of changes in position of the bell 16, but if the conductor operates the transmission 26 to turn the plug 8 through a suitable angle so as to present the jet *b* to the conduit 10 the feed of the fuel will increase in 25 proportion with the difference of feed between the said jets *a* and *b*. It can be understood that there will be again progressive increase of the proportion of fuel by again turning the plug 8 so as to successively place the sunk jets *c*, *d*, and *e*, 30 in concordance with the conduit 10. The carburetor according to the invention has consequently the advantage of allowing the conductor to adjust the gaseous mixture fed to the motor to the speed or power required by acting judiciously 35 on the bell 16 on the one hand and on the plug 8 on the other hand and without having often to cause the intervention of the change speed gear.
- For starting the motor for low speed and for slow running the feed of the smallest jet orifice *a* 40 is generally sufficient for admitting a small quantity of supplementary air which the driver regulates as required by raising more or less the bell 16. For medium speeds the conductor brings into use the jet *b* or the jet *c* as may be required. 45 For high speeds the jets *d* or *e* are utilized.
- The fraction of rotation given to plug 8 may be less than the interval separating two jets in order 50 to present before the hole 9 solid portion of the plug and prevent all feed of fuel without having to stop the vehicle when for instance it is travelling along a long descent of which the incline is sufficient to insure its running. This economizes the use of fuel during travelling over all important descents found in a journey.
- 55 For the purpose of facilitating that the conductor may exactly place the rotary plug 8 at the positions corresponding with the various sunk jets and the obtention of principal positions to be given to bell 16 to regulate the speeds of the 60 vehicle the two transmissions respectively governing plug 8 and the bell 16 may be actuated by a lever or other member provided with an index in cooperation with a dial sector which comprises suitable letters and indications.
- 65 It is evident that the number of sunk jets housed in the plug 8 as well as their respective sections and also the number of nozzles issuing into the chamber 11 can vary according to the types and powers of the motors.
- 70 It is to be remarked that in the drawings and the preceding description the level N. N. of the fuel in the tank 1 is specified below the chamber 11 since the said chamber constitutes the chamber for the emulsion of fuel and air in which is 75 produced a suction either exclusively by the mid-

dle tube 12 or simultaneously by the three tubes 12, 13, 14. But it is possible to raise the level of the fuel in the tank above the said chamber 11 in order that the latter will be constantly filled and that the lower orifices of the three tubes 12, 13, 14 are sunk in the fuel to directly suck the latter; in this latter case the atomization of the fuel is produced at the outlet of these tubes in mixture with air when the bell 16 is sufficiently raised.

An advantage of my carburetor is that it insures a perfect atomization of the fuel. In this respect, it will be observed that, owing to the closed lower end of nozzle 12, no drop of liquid may be projected directly from conduit 10 into the axial hole 12^a of said nozzle.

What I claim as my invention and desire to secure by Letters Patent of the United States is:—

1. In a carburetor, a constant level fuel tank; a mixing chamber situated above the fuel level in said tank; a connection between said tank and said chamber; a calibrated jet in said connection; a calibrated air inlet in said mixing chamber; a plurality of nozzle tubes communicating with said mixing chamber; a piston bell having in its base a plurality of blind bores of which one is an axial bore, said bores being adapted to accommodate said nozzle tubes; a fixed cylinder in which said piston bell is slideable; means to effect the sliding movement of said piston bell whereby said bores can be brought over said nozzle tubes to a greater or less extent; a suction pipe of substantially circular cross-section arranged substantially perpendicular to the axis of said fixed cylinder, said suction pipe being adapted to be closed by said piston bell; an air inlet in said fixed cylinder opposite to the entrance of said suction pipe; said piston bell having its axial bore in lateral communication with said air inlet through a radial hole and with said suction pipe through an inclined hole leading to the bell-mouthed end of a groove formed transversely on the base of said piston bell after a notch communicating with the base of said axial bore.

2. In a carburetor, a constant level fuel tank; a mixing chamber situated above the fuel level in said tank; a connection between said tank and said chamber; a calibrated jet in said connection;

120 a calibrated air inlet in said mixing chamber; a

plurality of nozzle tubes communicating with said mixing chamber; a piston bell having in its base a plurality of blind bores of which one is an axial bore, said bores being adapted to accommodate said nozzle tubes; a rod in said axial bore, said rod being angularly adjustable in po-

125 sition with respect to said piston bell, said rod being provided with an axial blind bore adapted to accommodate one of said nozzle tubes; a fixed cylinder in which said piston bell is slideable;

means to effect the sliding movement of said piston bell whereby said bores can be brought over

130 said nozzle tubes to a greater or less extent; a suction pipe of substantially circular cross-section arranged substantially perpendicular to the axis of said fixed cylinder, said suction pipe being

135 adapted to be closed by said piston bell; an air inlet in said fixed cylinder opposite to the entrance of said suction pipe; said piston bell having its axial bore in lateral communication with

140 said air inlet through a radial hole and with said suction pipe through an inclined hole leading to

145 the bell-mouthed end of a groove formed transversely on the base of said piston bell after a notch communicating with the base of the axial bore of said bell; and the axial bore of said axial

150 rod being provided with lateral holes and with

- 5 a notch adapted to register with the radial hole, the inclined hole and the groove of said piston bell whereby the section of passage from the radial hole of said piston bell to the axial bore 80 of said rod may be adjusted by angularly adjusting said rod in said piston bell. 85
- 10 3. A carburetor as claimed in claim 1, comprising an adjustable air inlet valve adapted to control the admission of air into the mixing chamber. 15
- 15 4. A carburetor as claimed in claim 1, wherein the nozzle adapted to enter the axial bore of the piston bell is closed at both ends and is provided at both ends with lateral holes. 20
- 20 5. In a carburetor, a constant level fuel tank; an inclined hole communicating with said tank; a rotatable tubular plug fitting in said hole; submerged calibrated jets arranged in ring-formation in the wall of said plug; a mixing chamber 90 situated above the fuel level in said tank; a conduit adapted to feed fuel into said mixing chamber, said conduit having its inlet in said inclined hole and so as to correspond with one of said submerged calibrated jets, whereby by turning 95 said plug the jet in operation may be varied and the fuel feed adjusted; means to retain said plug in axial position; means to control the angular position of said plug; a calibrated air inlet in said mixing chamber; a plurality of nozzle tubes communicating with said mixing chamber; a piston bell having in its base a plurality of blind bores of which one is an axial bore, said bores 100 being adapted to accommodate said nozzle tubes; a fixed cylinder in which said piston bell is slid- 105 able; means to effect the sliding movement of said piston bell, whereby said bores can be brought over said nozzle tubes to a greater or less extent; a suction pipe of substantially circular cross-section arranged substantially perpendicular to the axis of said fixed cylinder, said suction pipe being adapted to be closed by said piston bell; an air inlet in said fixed cylinder op- 110 posite to the entrance of said suction pipe; said piston bell having its axial bore in lateral com- 115 munication with said air inlet through a radial hole and with said suction pipe through an inclined hole leading to the bell-mouthed end of a groove formed transversely on the base of said piston bell after a notch communicating with the base of said axial bore. 120
- 45 6. A carburetor as claimed in claim 5, wherein the means to retain the plug in axial position comprises a pressure spring acting on the upper 125 end of the same. 130
